ICE TRAY

Logan Bleckley, Jr., Atlanta, Ga.

Application October 16, 1937, Serial No. 169,493

3 Claims. (Cl. 62—108.5)

This invention relates to ice making and more particularly to devices found in association with domestic refrigerators for freezing blocks or cubes of ice.

5 Heretofore it has been proposed to provide freezing pans having removable grids from which the ice could be removed by the application of hot water to the bottom portion of the ice pan, but not without considerable difficulty and waste. 10 It has also been proposed heretofore to provide a freezing tray with a plurality of separate cups for facilitating the removal therefrom by the application of hot water thereto but the method employed in securing the cups together has involved considerable difficulty in manufacturing 15 and expense.

It is an object of my invention to provide a freezing tray structure which can be readily and economically fabricated.

20 It is a further object of my invention to provide a freezing tray which will freeze ice quickly and which will facilitate the removal of frozen material therefrom.

25 Another object of the invention is to provide a freezing unit sans the usual removable grid or other removable parts in order that ice may be frozen and later obtained by simply holding the unit in inverted position under the faucet, whether part or all of the ice is desired.

30 A further object of the invention is to provide a freezing unit or tray, from which the ice is to be removed by heat exchange with water, so arranged that ice within the tray is not exposed to the water during the removal process.

35 Other objects and the nature and advantages of the invention will be apparent from the following description taken in conjunction with the accompanying drawing, wherein:

Figure 1 is a view in perspective of a modified 40 form of ice tray in accordance with my invention;

Figure 2 is an inverted sectional view taken along lines 9—9 of Figure 1;

Figure 3 is a view partly in section and partly 45 in elevation of the tray shown in Figure 1;

Figure 4 is a fragmentary plan view of the tray shown in Figure 1; and

Figure 5 is a fragmentary sectional view of a 50 tray slightly modified from that shown in Figure 1.

Referring to Figure 1, a plurality of the substantially rectangular parallelopiped panlike structures 60 which may be fabricated from sheet aluminum, or other suitable material are supported adjacent to each other with all their short

sides 61 in line longitudinally of the tray and all their long sides 62 in parallel relation transversely of the tray. The pans 60 are slightly tapered from top to bottom as shown in cross section in Figures 2 and 3, being slightly larger at the top than on the bottom in order to facilitate removal of ice therefrom. The long sides of the pans at their centers along a vertical axis are crimped to provide tapering V-shaped groove 65 in said pan as shown in detail in Figure 4 whereby a diamond 5 shaped conduit is provided for the passage of hot water applied to the bottom of said pan, or at the top when the pan is in inverted position as shown in Figure 1 in order that a sufficient quantity of hot water may pass in good heat exchange relation with the ice pan 60 to make for the quick, simple and neat removal of the ice with minimum waste thereof.

Supporting the pans in their assembled relation is a wire 66 about which are rolled the top lips 20 67 of the small sides 61 of the pans. The pans may or may not when assembled be arranged to touch each other along the sides 62 of their top edges. When it is desired that additional strength be given to the assembled structure, in my preferred form, I provide a sheet metal frame 68 which may be pressed to substantially rectangular shape as shown in Figure 1 which is arranged to be slipped about the assembly of pans before the application of the wire loop 66 and both the 25 upper lips of the pan and the entire upper lip 69 of the frame rolled over the wire loop as shown in cross section in Figure 2. Should additional strength be desired for the assembled structure, I may form the lower edge of the rectangular 30 frame with a roll as shown in cross section in Figures 2 and 3 which may or may not have therein a rectangular wire loop similar to that in the roll in the upper part of said frame. The upper 35 part of said frame at its ends 71 may be formed 40 to provide handles 72 as shown in Figure 1 and in cross section in Figure 3, to facilitate handling and removal of said tray.

In Figure 5 I have shown a fragmentary sectional view of a tray similar to that shown in Figures 1 to 4, inclusive but slightly modified in that it is intended to omit the V-shaped grooves 65 from the pans 60 and provide openings 65' at suitable locations in frame 68' about pans 60' 45 whereby when this form of tray is inverted under the hot water faucet, the hot water may pass in good heat exchange relation with the bottoms of the ice pans but will be discharged away from ice blocks which may fall from said inverted tray 50

into an ice block container placed beneath the inverted tray for that purpose.

Inherent in the construction of the trays in accordance with my invention which are described in this specification is the characteristic or property which facilitates the removal of the frozen material within said trays. The trays may be simply inverted under the hot water spigot in the kitchen for a relatively short period of time, said hot water passing in intimate relation with a relatively great portion of the area of said frozen material therein making for quick removal of said frozen material. Also inherent in the construction of the trays in accordance with my invention is the simplicity of fabrication from desirable materials and the accompanying low cost of manufacture.

It will be obvious to those skilled in the art that various changes may be made in this device without departing from the spirit of the invention and therefore the invention is not limited to what is shown in the drawing and described in the specification but only as indicated in the appended claims.

I claim:

1. An ice tray comprising a frame, independent cups nested in said frame and of a length to fit between the sides of the frame with their extremities engaging the frame, adjacent cups hav-

ing side wall portions in contact and side wall portions out of contact to provide water passages therebetween, said frame including a skirt serving to retain water around the underside of the cups when the tray is inverted and allowing water to escape through said passages, said cups and frame being fastened together to form a unitary tray, the construction and arrangement providing a liquid container when in upright position and when in inverted position serving to distribute liquid over the bottom of the cups and permit discharge of the same in a retarded manner for obtaining maximum heat transfer.

2. An ice tray comprising a frame, cups nested together and secured in said frame to form a tray, said cups having adjacent upper side wall portions in contact and adjacent upper side wall portions not in contact, said frame being constructed and arranged to confine a body of heat transmitting liquid to the underside of said cups when the tray is in inverted position so that such confined fluid may be discharged past the upper side wall portions which are not in contact.

3. The structure recited in claim 2, said frame including a skirt of a width substantially corresponding to the height of the cups and provided with spaced orifices for the escape of liquid therethrough.

LOGAN BLECKLEY, JR.
